PLOW BOTTOM

Carl V. Beckstrom, Moline, Ill., assignor to Deere & Company, Moline, Ill., a corporation of Illinois

Application November 12, 1936, Serial No. 110,497

10 Claims. (Cl. 97—113)

The present invention relates generally to plows and more particularly to plow bottoms having quickly detachable shares.

The principal object of my invention is to provide improved means for attaching the share to the frog of the plow bottom.

A further object is to provide attaching means which strengthens rather than weakens the plow structure. Other objects will be made apparent by a consideration of the following specification taken in conjunction with the drawing appended hereto in which:

Figure 1 is a perspective view of the underside of a plow bottom embodying the principles of my invention; and

Figure 2 is a similar view but with certain portions broken away to more clearly show the details of construction.

Referring to the drawing, the plow bottom 1 comprises generally a share 2, a moldboard 3, a landside 4, and a frog 5 which supports the other members in proper position relative to each other. The frog 5 comprises a heavy metallic plate which is bent to provide a slightly curved main supporting portion 6 and a landside portion 7 disposed in angular relation to the main portion 6. The moldboard 3 is rigidly bolted to the main portion 6 of the frog 5 by bolts 8. The landside 4 is rigidly attached to the landside portion 7 of the frog 5 by means of several bolts 9 secured by suitable nuts. The landside 4, as illustrated, is provided with a detachable heel 10 of conventional type fixed to the rear end of the landside by a pair of bolts 11. The share 2 comprises a blade portion 12 of conventional elongated rectangular shape, one of the longitudinal edges 13 of which is sharpened to provide a cutting edge, the opposite longitudinally extending edge 14 being adapted to fit closely in juxtaposition with the lower edge of the moldboard 3.

Along one edge of the share is a landside portion 15 of generally conventional shape, disposed at an angle to the blade portion 12. The landside 15 and one corner of the blade portion 12 are drawn out to provide the usual share point 16.

After the landside 4 and the moldboard 3 are bolted in proper position on the frog 5, the share 2 is adapted to take a position on the frog with the blade portion 12 in contact with the main supporting portion 6 of the frog and the landside portion 15 of the share in contact with the landside portion 5 of the frog and in alignment with the landside 4, the fitting edge 14 of the share lying in juxtaposition to the lower edge of the moldboard 3. Thus the main supporting portion

6 of the frog underlies both the moldboard 3 and the blade portion 12 of the share, while the landside portion 5 of the frog supports the landside 4 and the landside portion 15 of the share in proper alignment and in suitable angular position to the blade, the point 17 of the frog extending into the angle between the blade and the landside portion of the share toward the point 16 of the share.

Heretofore it has been common practice to provide an inwardly projecting lug on the landside portion of the share which engages a co-operative slot cut in the landside portion of the frog near the point 17 of the frog. It is well known to those skilled in the art, however, that during plowing the point of the frog is subjected to severe strains, for the reaction of the earth upon the point of the share tends to turn the latter downward into the ground and thus bend the point of the frog downwardly. Since it is obvious that a large slot disposed very near to the point of the frog has a weakening effect thereon and frogs have been known to bend at this point under severe conditions of plowing, in the present invention I have remedied this condition by providing an outwardly turned elongated flange 20 along the landside portion 7 of the frog 5, extending rearwardly from the point 17 of the frog. The landside portion 15 of the share is provided with an elongated recess or groove 21 extending longitudinally of the landside portion 15 substantially parallel to the bottom edge thereof. This groove 21 is adapted to receive the flange 20 on the frog, the flange and groove fitting together snugly to provide one means for attaching the share to the plow bottom. By this simple construction I have not only eliminated the slot in the point of the frog, but by the provision of the extra flange 20 I have greatly strengthened the frog point against downward bending. Although this construction requires the groove 21 in the landside portion of the share, this portion is appreciably thicker and the frog is therefore not weakened to the same extent. To further strengthen point 17 of the frog against bending, a dome-like bulge 22 is pressed into the main supporting portion 6 of the frog near the point 17. This bulge is convex on the bottom of the frog and is elliptical in form, the major axis of which is substantially parallel to the landside portion 7 of the frog.

The blade portion 12 of the share 2 is secured to the frog by means of a draw bolt 25 which engages a stud rivet 26 fixed in the blade 12 near the fitting edge 14 of the share, the bolt extend-

ing upwardly to an anchorage on the frog. This anchorage comprises a portion partly cut from the plate and bent outwardly to form a lug 27. An aperture 28 is provided in the lug 27 to receive the draw bolt 25. The end of the draw bolt is threaded and is provided with a nut 24 which bears against the lug 27. The stud rivet 26 is preferably stamped from a metallic plate and is provided with an undercut inclined camming surface 29, which is disposed on the side toward the cutting edge 13 of the share, converging relative to the surface of the blade 12 toward the fitting edge 14 of the share. A second surface 30 on the stud 26 extends from the inner edge of the inclined surface 29 and substantially perpendicular thereto to the surface of blade 5. The draw bolt 25 is in the form of an eyebolt having a flattened head 31 within which is disposed an aperture 32 adapted to receive the stud 26. The tip 33 of the head 31 is bent at an angle to the head to provide an inclined camming surface 34 adapted to cooperate with the undercut camming surface 29 of the stud 26.

A slot or notch 35 is cut in the main supporting portion 6 of the frog to receive the stud rivet 26, the frog extending past the rivet and terminating substantially at the middle of the share. The edge 36 of the frog plate at the inner end of the slot 35 constitutes a fulcrum for the draw bolt 25, which lies over the edge 36 in contact therewith. Since the edge 36 lies close to the stud rivet 26, the head 31 of the draw bolt when engaged under the stud rivet and lying over the edge of the plate is disposed at an acute angle to the surface of the blade. The shank of the draw bolt 25 is therefore bent at a point 37 above the fulcrum substantially parallel to the surface of the supporting portion 6 of the frog to bring it into alignment with the aperture 28 of the lug 27.

The bolt 25 is installed by inserting the threaded end through the aperture 28, then placing the head 31 over the stud rivet 26. The nut 24 is then applied to the threaded end of the bolt and by turning the nut against the lug 27, the bolt is drawn upwardly, or to the right as viewed in the drawing, until the camming surface on the tip 33 of the bolt head engages the undercut camming surface 29 on the stud rivet. Further tensional force on the bolt acting through the camming surfaces raises the share into contact with the supporting portion 6 of the frog, causing the shank of the bolt to bear upon the fulcrum edge 36. By increasing the tensional force on the draw bolt the tip 33 of the head is forced by the coaction of the camming surfaces in a downward direction, as viewed in Fig. 2, toward the blade 12, causing the head 31 of the draw bolt to be bent in a counterclockwise direction around the fulcrum edge 36, thus setting up a wedging action which presses the share and frog firmly together. When the inner edge of the tip 33 of the bolt head contacts the second surface 30 of the stud rivet, a further increase of tensional force in the draw bolt acting through the second surface 30 draws the fitting edge of the share firmly into engagement with the edge of the moldboard 3. Thus a tensional force in the draw bolt 25, obtained by turning the nut 24 against the lug 27, is resolved into two components of force, one component acting upon the stud rivet substantially perpendicular to the blade of the share, holding the latter against the frog and another component acting upon the rivet substantially parallel to the surface of the blade

holding the fitting edge 14 against the edge of the moldboard.

A third point of attachment of the share to the frog is provided by a bolt 40 near the rear end of the blade, close to the fitting edge 14. A second notch 41 in the edge of the frog plate is disposed to embrace the bolt 40 when in attached position, and a nut 42 acting against a washer 43 which bears upon the frog plate, secures the rear end of the share to the frog.

The share is quickly installed on the frog by first engaging the slot 21 in the landside portion with the flange 20 at the point of the frog, then slipping the head of the draw bolt over the stud rivet and tightening the nut 24, after which the nut 42 is tightened against the washer 43.

A diagonal bracing member 45 is provided between the landside portion 7 and the main supporting plate 6 of the frog for insuring rigidity between the parts. This brace is in the form of a rod, the ends of which are flattened and apertured to receive one of the bolts 8 of the main plate 6 and one of the bolts 9 in the landside portion of the frog. Further strengthening between the two angularly spaced portions of the frog is provided by a pair of spaced bulges 46 pressed inwardly on the apex of the frog. Another diagonal bracing member 47 is provided between the tip of the moldboard 3 and the plow beam (not shown), which is attached to the landside portion 7 of the share by suitable bolts for which apertures 48 in the frog are provided. This brace is of conventional type and is provided with conventional means indicated at 49 for adjusting it relative to the moldboard.

I claim:

1. In a plow body a detachable share comprising a blade portion and a landside portion disposed in angular relation to said blade portion, there being an elongated groove in said landside portion, and a frog comprising a plate adapted to lie along the blade portion of said share for supporting the same, said plate being bent to fit within the angle enclosed by said portions of the share to provide a supporting and reinforcing side plate adapted to lie against said landside portion of said share, a portion of one edge of said side plate of said frog being turned to provide a flange, said flange being adapted to fit within the groove in said landside portion of the share.

2. In a plow comprising blade and landside members disposed in predetermined relative angular relation, a frog comprising a plate formed to fit within the angle enclosed by said members for supporting and reinforcing the same, said frog having one edge turned outwardly to provide a flange adjacent the point of the frog for reinforcing the point against bending, said flange being adapted to engage said landside portion providing means for securing said frog to said landside.

3. In a plow comprising a share and a frog adapted to underlie and support said share, means for securing said share to said frog comprising a stud fixed to said share and a draw bolt anchored on said frog and engaging said stud, said stud and said bolt having cooperative camming surfaces whereby a tensional force applied to said bolt is resolved into components including a component acting substantially parallel to the axis of the stud and hence tending to hold said share against said frog.

4. In a plow comprising a moldboard, a detachable share, and a frog adapted to underlie

and support said moldboard and said share, means for fixing said moldboard to said frog, and means for securing said share to said frog comprising a stud fixed to said share and a draw bolt anchored to said frog and engaging said stud, said stud and said bolt having cooperative camming surfaces whereby a tensional force applied to said bolt is resolved into a component acting substantially perpendicularly to the surface of said share to hold the same against said frog, and another component acting substantially parallel to the surface of said share to hold the same in abutment with said moldboard.

5 5. In a plow comprising a share and a frog adapted to underlie and support said share, means for securing said share to said frog including a stud fixed to said share and a draw bolt anchored to said frog and extending over the edge of the latter to said stud, there being 10 cooperative camming surfaces associated with said stud and said bolt, respectively, whereby a tensional force applied to said bolt acts through said camming surfaces to force the end of said bolt toward said share and thus bending the bolt 15 over the edge of the frog.

15 6. In a plow comprising a share and a frog adapted to underlie and support said share, means for securing said share to said frog including a stud fixed to said share, a draw bolt 20 engaging said stud and lying over and bearing upon the edge of said frog, and a lug on said frog for attaching said draw bolt thereto, said stud having an undercut inclined surface converging with the surface of said share toward the fitting edge of the share, said draw bolt having a 25 cooperative inclined surface adapted to contact said surface on said stud.

30 7. In a plow body having a frog, a moldboard, and a detachable share comprising a blade portion and a landside portion, said landside por-

35 tion having an elongated depression disposed substantially parallel to the bottom edge thereof, means for locking the share to the frog comprising an outwardly turned flange on said frog adapted to fit within said depression in said landside portion, a stud rivet fixed to the bottom of said blade portion, said stud rivet having a camming surface disposed at an acute angle to the axis of said rivet, and a draw bolt having a camming surface at one end thereof disposed in cooperation with said camming surface on said stud, said bolt extending over the edge of said frog to a point of attachment near the other end of said bolt, whereby a tensional force on said bolt acting through said camming surfaces forces the end of said bolt toward said share and thus causing the side of the bolt to bear upon the edge of said frog.

40 8. As an article of manufacture, a plow frog comprising a wrought metal plate, one edge of said plate adjacent the point of the frog being turned to provide a flange adapted to fit within a suitable recess in another member of a plow body for the purpose of attaching said member and said frog together.

25 9. As an article of manufacture, a plow frog comprising a metal plate, a portion of one edge of said plate adjacent the point of the frog being extended to provide an integral projecting tongue adapted to interfit with other parts of a plow 30 body in assembly.

35 10. As an article of manufacture, a plow frog comprising an integral metal plate having a main supporting portion and a landside portion turned at an angle to said main portion, a portion of one edge of said landside portion being turned out of the plane of said landside portion to provide a locking tongue, adapted to interlock with other parts of a plow body in assembly.

CARL V. BECKSTROM.
